FURNITURE FASTENING DEVICE
Hans Juergens Abramowski, Chicago, Ill., assignor to
Khouri Bros., Inc., Iron Mountain, Mich., a corpora-
tion of New Jersey
Filed Nov. 9, 1961, Ser. No. 151,600
3 Claims. (Cl. 211—134)

This invention relates to fastening devices in the form of hooks for holding furniture in assembled relationship.

At the present time a great many articles of furniture are shipped in knocked down form and assembled by the purchaser in his house or office. This makes possible the shipment of the furniture by express, or even smaller articles by parcel post, instead of the slower and more costly freight. A problem arises, however, in that the buyers of the furniture frequently lack mechanical skill and do not have the tools with which to put the furniture together.

The object of the present invention is to provide a fastening device in the form of a hook by which knocked down furniture may be readily assembled and held together.

A further object of the present invention is to provide a fastening device for assembling knocked down furniture which does not require any mechanical skill on the part of or the use of tools by the person assembling same.

Another object of the present invention is to provide a fastening device for assembling knocked down furniture which may be readily made of commercially available material.

Still other objects, advantages, and improvements will become apparent from the following specification, taken in connection with the accompanying drawing, in which:

FIGURE 1 is a front elevational view of an article of furniture having three columns and two tiers of shelves held together by the fastening devices according to the present invention;

FIGURE 2 is an end elevational view of the article of furniture shown in FIG. 1;

FIGURE 3 is an under plan view, partly in section, taken on the section line 3—3 of FIG. 1 and looking in the direction of the arrows;

FIGURE 4 is an isometric view showing two shelves secured to two vertical frame members by the fastening devices according to the present invention;

FIGURE 5 is an isometric view of two of the single fastening devices according to the present invention; and

FIGURE 6 is an isometric view of a double fastening device according to the present invention.

Referring now to the drawings in detail, and to FIG. 1 in particular, there is here shown an article of furniture which is comprised by two end sections, two intermediate sections, and a series of shelves. Each end section is comprised in part by two vertically positioned frame members 10—10, and each intermediate section is comprised in part by two vertically positioned frame members 12—12. As shown in FIG. 2, the end frame members 10—10 are joined together by upper, intermediate, and lower horizontal frame member 11. The intermediate frame members 12—12 are similarly joined together. The lower and intermediate horizontal frame members 11 are secured to the vertical frame members 10—10 and 12—12 by the well known mortise joint; the upper horizontal frame members 11 are secured to the vertical frame members 10—10 and 12—12 by a tongue and slot joint.

As shown in FIG. 1, lower shelves 13 and 17 and a series of upper shelves 18 are secured between the vertical end frame members 10—10 and the vertical intermediate frame members 12—12 in all three columns by

2

the fastening devices according to the present invention. In the left column hinged doors 14 are provided over the front of the compartment between the end frame members 10—10 and the intermediate frame members 12—12 and between the shelves 13 and 17, the hinges for these doors not being shown. One door 14 will be secured by a pair of hinges to the left front end frame member 10 and the other door 14 by a pair of hinges to the left front intermediate frame member 12, when the sections are assembled at the factory.

In the middle column a shelf 16 is provided between the shelves 13 and 17. Also a desk lid (not shown) is preferably held by hinges to the shelf 17. In this case the shelf 18 immediately above the shelf 17 will preferably be narrower than the other upper shelves 18 by at least the thickness of the desk lid, so that the desk lid will fit flush with the frame face of the intermediate frame members 12—12 when in the closed position.

In the right column tiers of drawers 20 are positioned in the compartment between the vertical end frame members 10—10 and the vertical intermediate frame members 12—12 and between the shelves 13 and 17. These drawers are slidably mounted on runners (not shown), which runners are also secured to the end frame members 10—10 and the intermediate frame members 12—12, when the sections are assembled at the factory.

The vertical end frame members 10—10 are preferably provided with longitudinal grooves from their tops to the lower horizontal frame members 11, the latter frame members are provided with grooves in their tops, and the intermediate horizontal frame members 11 are provided with grooves in their tops and bottoms, all the grooves being aligned in the same vertical plane. A lower panel (not shown) is mounted between the vertical end frame members 10—10 and in the grooves in the latter and between the lower horizontal and intermediate frame members 11—11 and also in the grooves in the latter. Similarly, an upper panel (also not shown) is mounted between the vertical end frame members 10—10 and in the grooves in the latter, and in the groove in the top of the intermediate horizontal frame member 11. This latter panel, however, terminates at the level of the uppermost shelf 18.

The single fastening device according to the present invention is shown in FIG. 5 and is designated generally by the reference numeral 24. This device is used for securing the shelves to the vertical end frame members 10—10. It is made of rod material and is comprised by a horizontal section 24a, a downwardly extending vertical section 24b at right angles to the horizontal section 24a, an outwardly extending horizontal section 24c at right angles to the horizontal section 24a and the vertical section 24b, and an upwardly extending vertical section 24d at the end of the horizontal section 24c disposed in parallel relationship to the first vertical section 24b.

The double fastening device according to the present invention is shown in FIG. 6 and is designated generally by the reference numeral 25. This device is used for securing shelves on both sides of the intermediate vertical frame members 12 to the latter. It is likewise made of rod material and is comprised by a horizontal section 25a, a downwardly extending vertical section 25b at right angles to the horizontal section 25a, oppositely extending horizontal section 25c at right angles to the horizontal section 25a and the vertical section 25b, and upwardly extending vertical sections 25d—25d at the ends of the horizontal sections 25c—25c, disposed in parallel relationship to the first vertical section 25b.

The vertical end frame members 10—10 and the vertical intermediate frame members 12—12 are provided with holes 23 on their inner sides at the levels where

the shelves 16, 17, and 18 are to be placed. The horizontal sections 24a of the single fastening devices 24 are received in the holes 23 in the vertical end frame members 10-10 and the horizontal sections 25a of the double fastening devices are received in the holes 23 in the intermediate vertical frame members 12-12. Similarly, the shelves 16, 17, and 18 are provided with holes 26, which are spaced inwardly from their sides a distance at least equal to the width of the vertical end frame members 10-10 and the vertical intermediate frame members 12-12, and which are spaced from the ends of the shelves a distance equal to the length of the horizontal section 24c of the single fastening devices 24 and the lengths of the horizontal sections 25c of the double fastening devices 25. The holes 26 are drilled from the bottom of the shelves and preferably do not go all the way through same. At the outer ends of the shelves the holes 26 receive the vertical sections 24d of members 10-10; similarly, at the inner ends of the shelves the holes 26 receive the vertical sections 25d of the double fastening devices 25 on the intermediate vertical frame members 12-12. As shown in FIGS. 1 and 3, through the use of the double fastening devices 25 the shelves on both sides of the intermediate vertical frame members 12-12 may be supported at one end by a single fastening device.

It will be understood that the hooks are reversible. In other words, they can be used from the top down. Furthermore, there is no limitation in using these hooks as regards size such as depth and width of the shelves or cabinets to be hung in any arrangement as pleased. When in use, the hooks are almost invisible to the eye as less than 30% thereof will show. As regards the hooks being reversible, this is for the purpose of holding cross members in place in shipment since it is readily apparent that when the hooks are reversed, the hook will not support any downward weight, but will prevent side slipping of the cross member or cabinet.

I claim:

1. A fastening device for securing together two members of an article of furniture comprised of a horizontal section, a vertical section at right angles to the horizontal section, a second horizontal section at right angles to the first horizontal section and the vertical section, and a second upwardly extending vertical section at the end of and disposed at right angles with respect to the second horizontal section, all of said sections being formed from a single piece of metal of uniform circular cross-section and all of said sections being substantially straight.

5 2. A fastening device for securing together three members of an article of furniture comprised of a horizontal section, a vertical section at right angles to the horizontal section, a second horizontally extending horizontal sections at the end of said vertical section disposed at right angles with respect to the first horizontal section and the vertical section, and additional vertical sections respectively at the ends of and disposed at right angles with respect to the latter horizontal sections.

15 3. A fastening device for securing together three members of an article of furniture comprised of a horizontal section, a vertical section at right angles to the horizontal section, oppositely extending horizontal sections at the end of said vertical section disposed at right angles with respect to the first horizontal section and the vertical section, and additional upwardly extending vertical sections respectively at the ends of and disposed at right angles with respect to the latter horizontal sections.
